UNITED STATES PATENT OFFICE.

MARTIN W. BRUESHABER, OF CHICAGO, ILLINOIS, ASSIGNOR TO GOSS PRINTING PRESS COMPANY, A CORPORATION OF ILLINOIS.

STEREOTYPE PRINTING PLATE.

Original application filed March 21, 1921, Serial No. 454,001. Divided and this application filed January 21, 1922. Serial No. 530,945.

To all whom it may concern:

Be it known that I, MARTIN W. BRUESHABER, a citizen of the United States, residing at Chicago, in the county of Cook and State of Illinois, have made certain new and useful Improvements in Stereotype Printing Plates, of which the following is a specification.

The invention relates to a novel stereotype printing plate and more particularly to novel features in a curved, end poured stereotype plate.

Objects and advantages of the invention will be set forth in part hereinafter and in part will be obvious herefrom, or may be learned by practice with the invention; the same being realized and attained by means of instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:—

Fig. 1 is a central longitudinal section through part of a casting machine adapted to cast the plate of the invention;

Fig. 2 is a fragmentary perspective of the end of the cast plate with the multi-part riser;

Fig. 3 is a vertical transverse section on line 3—3 of Fig. 1;

Fig. 4 is a like section, but taken in the casting position and showing the core.

This application is a division of my co-pending application Ser. No. 454,001, filed March 21, 1921, now Patent No. 1,514,757, dated Nov. 11, 1924.

The plate of this invention by its novel features cooperates especially with a novel plate casting mechanism, which machine is built very much along standard lines so far as concerns its general features, while adding thereto, or introducing thereinto, novel features and instrumentalities operating or conduced to render the machine largely automatic or approximately so; to facilitate the discharge and the handling of the hot plate preparatory to finishing; to quickly

and easily strip the cast plate from the matrix and to separate or space it from the wall of the drag preparatory to its removal from the casting machine, either manually or by a machine, and to effectuate the foregoing by simple, sturdy and reliable mechanism, operating automatically in the ordinary operation, or by the usual movements, of the parts of the casting machine. Other features and objects than those enumerated will be set forth in connection with the detailed description of the machine.

In the embodied form, devices are provided engaging with each end, preferably each arcuate end, of the cast plate to lift the plate clear from the matrix and the wall of the drag. Preferably in connection therewith, as embodied, a plate is cast having a tail at either end, or a tail at the bottom and a riser at the top, the plate lifting devices engaging with the two tails, and lifting the plate clear of the matrix and the drag wall, and thereby positioning the plate so that it may be removed either manually or by mechanism without danger or injury to the matrix or to the plate.

As embodied further, the plate lifting members are nested in the wall of the drag during the casting operation and are projected from their nests or seats to lift the plate as described. The plate lifting members are preferably two arcuate saddles nested in recesses in the drag wall and, when projected, engaging the tails at either end of the plate to strip it from the matrix and lift it free from the drag. The saddles are preferably spring pressed into their nests and are automatically moved therefrom to lift the plate from the matrix and the drag wall.

The stereotype plate of this invention is cast in a casting machine having a vertical stationary core and a traveling drag, as shown in the parent case.

Referring now to the construction of the automatic plate-removing means, and to certain of the cooperating parts, there are provided suitable end stops 46 and 47, to protect the ends of the matrix 45 from the hot poured stereotype metal and to form wholly or in part the curved beveled ends of the plate. Suitable devices may be provided for holding the straight edges of the matrix in position within the box or drag 3, and

these may be of any suitable or adequate form, the same not being shown herein.

In the embodied form, and according to one feature of the invention, the casting chamber is shaped to cast a plate 48 with an intermediate printing portion 49 (which is the plate proper, that is, it carries the operating surface of the finished plate which goes upon the form cylinder of the press), 5 with an arcuate riser 50 at one curved end, and with an arcuate tail 51 at the opposite curved end of the plate from the riser. The embodied form of plate removing mechanism cooperates with these two tails 50 and 51 at the opposite curved ends of the plate, and said mechanism preferably does not engage with the plate proper 48.

The embodied form of plate removing means lifts the plate bodily from the matrix 20 and drag, and brings it to rest as shown in Figs. 1 and 3, preparatory to the removal of the plate, either by mechanism or by hand. The two mechanisms so operating may be of the same or similar construction and will 25 be described together. As embodied two arcuate yokes 56, one at either end of the plate, and of like curvature and size or radius with the exterior of the stereotype plate 48 are nested or seated within a recess 30 57, formed either in the wall proper of the drag or in a recess in the head stop 47 and tail stop 46, as may be found most convenient or advisable.

Means are provided for projecting the 35 yokes 56 from the nests or recesses 57 at the plate-discharging position, to bring the cast plate to a position such as is shown in Figs. 1 and 3. In the embodied form of such means, there is fixed to each of the yokes 56 a stem 58, projecting backwardly through an aperture in the back wall of the drag, and 40 preferably located centrally with respect to the curved shape or dimension of the drag. Within this aperture is a bushing or sleeve 59, provided at its inner end with a shoulder 60. Coiled about stem 58, and in compression between the shoulder 60 of bushing 59 and a collar 61 fixed upon the outer end of stem 58, is a spring 62. In the outer end 45 of each of the stems 58 there is preferably a friction wheel 63. Keys or splines 64 are provided to prevent rotation of the stems 58 when the saddles are projected, that is, are out of their seats 57.

The springs 62 operate to press the corresponding yokes or saddles 56 into their seats in the wall of the drag, as shown in Fig. 4. Means are provided operating automatically as the casting box comes to the plate-discharging position of Fig. 1, to engage with the stems 58, and to move them against the springs 62 to the position of Fig. 3 to bring the plate to discharging position.

In the embodied form of actuating means 55 for the saddles, the right-hand stem 58, or

its roller 63, in Fig. 1, as the drag comes to the plate discharging position, engages with an arm 68, fixed on a shaft 69, which shaft is mounted in fixed or non-rotating position in the machine frame. As embodied, the 70 corresponding mechanism, operating upon the stem 58 or its roller 63 at the left hand end of Fig. 1, comprises a lever 70, fixed on a shaft 71, which is journaled at 72 and 73 in the machine frame. At one of its ends 75 lever 70 is provided with a friction roller 76, adapted to engage with a lug 77 when the drag comes to the plate-discharging position. Lever 70 is thus rocked such a distance that its opposite end engaging with 80 roller 63 will impart to its saddle movement equal to that of the other saddle 56, so that the plate 48 will be moved or lifted throughout its length an equal distance and is thus stripped from the drag 3 and from the matrix 45.

In Fig. 4 one of the saddles 56 is shown nested in the drag wall during the casting operation.

In Fig. 3 part of a mechanical, automatically operating plate remover 80 is shown, 90 cooperating with the plate as positioned for discharge by the mechanism hereinbefore described. This device, shown by way of example, is the carrier illustrated and described in copending application Ser. No. 407,987 filed Sept. 3, 1920 of Albert A. Henzi now Patent 1,467,790 dated Sept. 11, 1923.

The carrier 80 rotates in the direction of 100 the arrow in Fig. 3, and the edge 81 thereof engages with the edge of plate 50, carrying the plate around to a position on top of the carrier 80, and it is then removed for delivery or to the machine of which the 105 carrier 80 forms a part in said copending application.

In this application the casting box is shown with a solid back, while in the parent case there is also shown a two part drag, 110 that is, a drag having a receding back portion movable to and away from the matrix sheet, the same or similar to that shown in copending application of Albert A. Henzi, Ser. No. 408,203 now Patent No. 1,509,078, 115 dated Sept 16, 1924. In Figs. 1, 3, and 4, the plate lifting saddles and the end rings for the matrix sheet are shown separate from each other and movable relatively to each other.

One arcuate end of the plate 48 is provided with inwardly extending projections 111 and intervening recesses 112, the casting core being suitably shaped for forming such projections and recesses. The projections 111 are particularly useful as furnishing hand-holds for the workman, whereby the handling of the plate is facilitated.

The invention in its broader aspects is not limited to the specific mechanisms shown 130

and described but departures may be made therefrom within the scope of the accompanying claims without departing from the principles of the invention and without sacrificing its chief advantages.

5 What I claim is:—

1. A hemi-cylindrical printing plate having two straight edges and two arcuate edges, one end comprising an arcuate tail 10 and the other arcuate end comprising an arcuate riser, the convex side of said tail and riser being curved to fit into concave lifting yokes for facilitating a quick removal of the plate from the matrix.

2. A hemi-cylindrical printing plate having a curved tail at one end and a correspondingly curved multipart riser at the other end, the riser having projections and recesses along its outer edge, the convex side of the tail and of the riser being curved to fit into concave lifting yokes for facilitating a quick removal of the plate from the matrix, the projections on the riser furnishing handholds for still further facilitating rapid handling of the plate.

15 20 25
In testimony whereof, I have signed my name to this specification.

MARTIN W. BRUESHABER.
